LOOSE LEAF BINDER

George W. Newman, St. Louis, Mo., assignor to
 Loose Leaf Metals Company, a corporation of
 Missouri

Application January 12, 1935, Serial No. 1,458

3 Claims. (Cl. 129—24)

The invention relates to loose leaf binders of the type in which mating sheet carrying arches are supported by a pair of toggle elements, controlled by spring means.

5 The object of the invention is to provide improved means for limiting the action of the toggle joint; and it consists in providing the toggle elements with interfitting ribs and grooves, one or both of them being provided with a projecting and outwardly inclined marginal flange or lip overlapping a face of the companion element and limiting the range of movement of the toggle.

In the accompanying drawing:

Fig. 1 is a perspective view of a binder embodying the invention; and

Fig. 2 is an end view thereof.

While I have shown two forms in which the invention may be embodied, it may be given other forms, and though I have shown only toggle elements in the form of plates, other forms may be employed, as the invention pertains to the engaging margins of the toggle elements and is not concerned with the character of their body portions.

25 The binder as illustrated comprises a pair of toggle plates 10, 11, each carrying toggle arches 12, 13, arranged in mating pairs. The plates 10, 11, are clamped together by means of a spring arch plate 14, the margins of which overlap the outer edges of the toggle plates. As thus far described the binder is of known construction.

In such binders it is necessary that the outward flexing of the toggle elements be limited and there are advantages in having means, other than the meeting of the arch elements, for limiting the inward flexure of the toggle. Numerous forms of limiting means have heretofore been provided, but they are quite expensive of manufacture and have other disadvantages.

40 In the present invention the toggle elements are so interengaged that integral limiting means are provided.

In the preferred form of construction, illustrated in Figs. 1 and 2, the inner or meeting edges of the two plates 10, 11, are of identical form, each being longitudinally channeled, and consequently have tongue and groove engagement. One of the tongues or ribs of each of the plates, as shown at 15, 16, is short, these two short ribs serving as

50 hinge journals. The companion ribs, as 17, 18,

each project as a flange a substantial distance from the inner margin of the plate, and are each inclined outwardly from the plane of the corresponding plate, are on opposite sides of the toggle, and limit the extent to which the joint may be flexed.

As shown in Fig. 2, the lower flange 18 on the plate 10 comes into engagement with the lower face of the companion plate 11 when the arches are opened, thus limiting the opening movement 10 and preventing the disassembling of the parts of the binder by the action of the spring plate. As shown in Fig. 1, the upper flange 17 comes into engagement with the upper face of the plate 10 when the arches are closed, relieving the latter in 15 part of the duty of resisting the spring compression.

The two toggle plates are identical in form. They are shaped up by a suitable machine, and may be formed in long strips and then cut to 20 suitable length. In assembling, one plate of a pair is overturned endwise. The flexure of the joint is limited by the engagement of the projecting flange of one plate with the face of the other plate, and the interlocking of the two shorter ribs. 25

I claim as my invention—

1. In a loose leaf binder, in combination, a pair of toggle plates having interfitting margin ribs and grooves, one of the plates having a forwardly projecting and outwardly inclined flange overlapping the companion plate, mating prongs carried by the plates, and spring means clamping the plates together.

2. In a loose leaf binder, in combination, a pair of toggle plates having interfitting margin ribs 35 and grooves, each of the plates having a forwardly projecting and outwardly inclined flange overlapping the companion plate, mating prongs carried by the plates, and spring means clamping the plates together.

3. In a loose leaf binder, in combination, a pair of edge to edge mating toggle plates each having a marginal V-groove and a short rib interfitting with the groove of the companion plate and an elongated rib overlapping the companion plate, 45 the elongated ribs being oppositely disposed, mating arch prongs carried by the plates, and a bowed spring for clamping the plates together.
